(57) **CLAIM**

The ornamental design for a substrate for an electronic circuit, as shown and described.

DESCRIPTION

FIG. 1 is a perspective view of a substrate for an electronic circuit showing our new design;

FIG. 2 is a rear perspective view thereof;

FIG. 3 is a front elevational view thereof;

FIG. 4 is a rear elevational view thereof;

FIG. 5 is a right side elevational view, a left side elevational view being a mirror image thereof;

FIG. 6 is a top plan view thereof; and,

FIG. 7 is a bottom plan view thereof.

The broken lines shown in the drawings represent portions of the substrate for an electronic circuit that form no part of the claimed design.
